HANDLE FOR ACCOMMODATING PRESURIZED CYLINDER CLOSURES

Frederic W. Hammesfahr, Bethlehem, Pa., assignor to
J. T. Baker Chemical Company, Phillipsburg, N.J., a
corporation of New Jersey

Filed Nov. 7, 1963, Ser. No. 77,325

Term of patent 14 years

(Cl. D16—2)

FIG. 1

FIG. 3

FIG. 4

FIG. 2

FIGURE 1 is a top plan view of the handle for accommodating pressurized cylinder closures embodying my new design.

FIGURE 2 is a side elevational view thereof.

FIGURE 3 is a bottom plan view thereof.

FIGURE 4 is a cross section taken along line 4—4 of FIGURE 1.

The cylinder is fragmentarily shown in broken lines for purposes of illustration only.

I claim:

The ornamental design for a handle for accommodating pressurized cylinder closures, substantially as shown and described.
